US00D883549S

(12) **United States Design Patent** (10) Patent No.: **US D883,549 S**
(45) Date of Patent: ** May 5, 2020

(54) **STAND LIGHT**(71) Applicant: **MILWAUKEE ELECTRIC TOOL CORPORATION**, Brookfield, WI (US)(72) Inventors: **Kyle Harvey**, Wauwatosa, WI (US); **Ross McIntyre**, Milwaukee, WI (US); **Eric Mackey**, Milwaukee, WI (US); **Justin Dorman**, Wauwatosa, WI (US)(73) Assignee: **Milwaukee Electric Tool Corporation**, Brookfield, WI (US)(**) Term: **15 Years**(21) Appl. No.: **29/689,503**(22) Filed: **Apr. 30, 2019**

(57) **CLAIM**

We claim the ornamental design for a stand light, as shown and described.

DESCRIPTION

The FIGURE is a perspective view of a stand light. Portions of the stand light shown in broken lines are for illustrative purposes only and form no part of the claimed design.
